CONTINUOUS KILN

Filed March 28, 1929

Inventor:

Charles Burton Winzer

By John Goulding
Attorney

UNITED STATES PATENT OFFICE

CHARLES BURTON WINZER, OF CLAPHAM, LONDON, ENGLAND

CONTINUOUS KILN

Application filed March 28, 1929, Serial No. 350,569, and in Great Britain March 8, 1928.

This invention relates to continuous ovens or kilns for firing pottery goods at higher or lower temperatures, but the apparatus, with certain structural alterations, may also be used for other purposes such as the annealing of steel plates, the firing of bricks or for drying materials.

The chief object of the present invention is to provide an efficient apparatus wherein the firing or heating will at all times be uniform and regular and wherein the goods remain stationary throughout the treatment.

In accordance with the present invention the goods or material to be treated are placed on or in stationary carriers or placed upon a stationary platform or hearth within a travelling tunnel having heating and cooling zones, the former furnished with or provided by coal, gas, oil or other furnaces.

Referring to the accompanying drawing:

Fig. 1 is a sectional elevation, partly diagrammatic, of an apparatus constructed in accordance with or embodying the present invention, and

Fig. 2 is a plan of the apparatus shown in Fig. 1.

A is the travelling tunnel, B are the cages for the goods or material and D is the stationary platform.

In the embodiment of the invention chosen for illustration and explanation the apparatus is of circular formation, providing a continuous or endless tunnel, but it may be constructed in a straight form; the present embodiment being particularly applicable for firing pottery goods.

The carriers or cages B for holding the goods are placed on an upper platform or hearth C which is made up of separate, movable sections of fireclay blocks that fit closely against each other and thus form an unbroken or continuous annular support; and these sections are each mounted on wheels C¹ adapted to run on rails E on the lower platform D. The rails E (see Fig. 2) are arranged in pairs running radially across the platform at suitable intervals or distances apart around its entire circumference.

The travelling tunnel A, which may be

constructed in any appropriate manner and of suitable materials, has a roof and side walls which enclose or embrace saddlewise the hearth or sectional platform C and the carriers B for the goods. This tunnel is furnished with inner and outer sets of wheels or runners A¹, A² adapted to run on tracks F, F¹ which conveniently are sunk below the level of the hearth.

The lower ends of the tunnel walls overlap slightly the edges of the platforms C and D, and the inner walls of the tunnel are furnished with plates a, a¹ which enter channels b, b¹ arranged around the inner and outer edges of the platform D. These channels may be filled with sand or other material to form seals and so prevent or minimize the ingress of air to the tunnel.

The tunnel is driven by any suitable gear indicated diagrammatically at G, and the necessary heat may be supplied to it in various manners. In the present embodiment three combustion chambers or furnaces H are provided and are situated on the inner side of the travelling tunnel. Producer gas from a centrally situated supply pipe J is conveyed to the combustion chambers H by a radially disposed pipe J¹ which leads into a manifold or distributor J² having branches leading to each combustion chamber.

The waste gases are withdrawn from a cool zone of the tunnel by a pipe or flue K which communicates with a discharge pipe or chimney L arranged axially above the supply pipe J.

Approximately diametrically opposite the furnaces and therefore in a cool zone of the tunnel there is situated a loading and discharge opening furnished with a sliding or otherwise movable door M.

Alongside this door or opening is arranged a short travelling platform N mounted on wheels N¹ adapted to run on a continuous track N²; and adjacent said door there are mounted two other sliding doors O, O¹ a little more than the length of a section apart, said doors O, O¹ extending across the tunnel.

When the tunnel is travelling the door M is closed and the doors O, O¹ are withdrawn or are open. When it is desired to with-

draw a section of the platform or hearth C and its cage or carrier B with the fired goods therein, the doors O, O¹ are closed to isolate the particular section and carrier from the others and to prevent escape of the heating gases from or the ingress of air to the tunnel. After the doors O, O¹ have been closed the outer door M is opened and the hearth section and carrier can be moved out of the tunnel on to the travelling platform N.

This travelling platform, in addition to moving with the tunnel, is also capable of a certain amount of movement relatively to the tunnel so that when a hearth section and carrier have been moved out of the tunnel, a fresh or waiting hearth section with unfired goods can be brought opposite the doorway and moved into the tunnel. When this fresh section has been moved into the tunnel, the outer door M is closed and the cross-doors O, O¹ are again opened.

Additional heating flues may be provided to conduct heat to or under the hearth.

As the goods, once within the tunnel, are stationary throughout the firing process, they are not subjected to shocks or vibrations.

During the travel of the heating tunnel the goods, placed first in a cool zone, are subjected to a gradually rising heat, and this heat is applied equally in turn to all the goods so that uniform firing is obtained throughout the tunnel and the heat is uniform at the top, bottom and sides of the carriers.

As the loading and unloading platform N travels with the tunnel, the goods can be loaded and unloaded around the entire circumference of the tunnel.

What I claim is:—

1. In a continuous kiln, the combination of an annular rotary tunnel having a combined loading and discharge opening in its outer wall; driving means for said tunnel; means for heating the interior of the tunnel; an upper and a lower stationary annular platform enclosed in superposed relation within the confines of the tunnel, the upper platform embodying a circular series of sections capable of individual movement radially through said opening; an annular track encircling the tunnel in proximity to its outer wall; and a platform mounted opposite the said opening to travel with the tunnel along said track, each section of the upper platform adapted to support a removable goods carrier which is withdrawn with the corresponding section through said opening onto the travelling platform.

2. A kiln according to claim 1, in which a movable door is provided for the loading and discharge opening to open and close the same, and additional movable doors are provided within the tunnel to isolate a platform section and its goods carrier about to be run through said opening.

3. A kiln according to claim 1, in which

the travelling platform is mounted to have a movement of limited extent along the track relative to the tunnel, in addition to its movement with the tunnel, so as to enable a fresh section and a carrier containing unfired goods to be moved from the platform through the tunnel opening and into the interior of the tunnel to take the place of the section and carrier withdrawn.

4. A kiln according to claim 1, in which the means for heating the interior of the tunnel comprises a combustion chamber attached to the inner wall of the tunnel, a gas supply pipe disposed centrally of the tunnel and having a branch leading from it to said chamber to deliver the gas thereto, and an exhaust pipe for the spent gases leading from the tunnel.

In testimony whereof I affix my signature.
CHARLES BURTON WINZER.
